UNITED STATES PATENT OFFICE.

JOHN MOFFET, OF BAYONNE, NEW JERSEY.

REVERSIBLE ENGINE.

SPECIFICATION forming part of Letters Patent No. 440,491, dated November 11, 1890.

Application filed January 27, 1890. Serial No. 338,259. (No model.)

To all whom it may concern:

Be it known that I, JOHN MOFFET, a citizen of the United States, residing at Bayonne, in the county of Hudson and State of New Jersey, have invented certain new and useful Improvements in Reversible Engines; and I do hereby declare the following to be a full, clear, and exact description of the invention, such as will enable others skilled in the art to which it appertains to make and use the same.

My present invention relates to that class of rotary engines having a vertically-elongated shell or casing inclosing a slotted cylinder provided with sliding piston-blades, the ends of the rotary cylinder being recessed to enable it to pass around a cam, one of which is secured to each head of the casing for the purpose of successively projecting the piston-blades as the cylinder is rotated, an example of which form of engine is shown in my previous patent, No. 315,318, dated April 7, 1885, the object of the present improvements being to make such an engine reversible, and to simplify, perfect, and add to the efficiency of the same; and to this end my invention consists in the construction, arrangement, and combination of parts, substantially as will be hereinafter described and claimed.

In the accompanying drawings, illustrating my invention, Figure 1 is an elevated view of the exhaust end of my improved reversible engine. Fig. 2 is a longitudinal section on the line $x x$ of Fig. 1. Fig. 3 is an elevation of the steam end of the piston, the parts being shown in the reversed position. Fig. 4 is an inner vertical end elevation at the exhaust end of the engine, the casing-head and other outer parts being removed. Fig. 5 is a section on the line $x' x'$ of Fig. 3. Fig. 6 is an enlarged elevation of the exhaust-valve. Fig. 7 is a transverse section on the line $y y$ of Fig. 6. Fig. 8 is a cross-section on the line $y' y'$ of Fig. 6. Fig. 9 is an enlarged elevation of the steam-valve. Fig. 10 is a cross-section on the line $z z$ of Fig. 9. Fig. 11 is a partial section on the line $z' z'$ of Fig. 9.

Similar letters of reference designate corresponding parts throughout all the different figures of the drawings.

A denotes the vertically-elliptical shell or casing, which is of suitable size and form.

Within casing A is the internal rotary cylinder B, the ends of which are recessed at B' B' to receive the vertically-elongated cams C 55 C, one of which is secured to the inner side of each casing-head F and G.

D indicates the shaft or journal of the rotary cylinder B. This cylinder is formed with radial longitudinal slots, wherein are the sliding piston-blades E E. There are preferably eight of these blades, arranged as shown.

At one end of the shell or casing A is the head F, which serves as the steam-cover, and at the other end of the casing the head G, 65 which serves as the exhaust-cover. The head F contains the steam-valve H, (shown in detail in Figs. 9, 10, and 11,) and consists of a metallic wheel or annular ring made hollow or formed with a circular recess h. A 70 segment h' of the peripheral edge of the valve H at the upper side thereof is toothed or provided with gear-indentations; also, the valve H has two pairs of similarly-disposed ports situated in opposite parts of the valve, as 75 shown, a a being the upper ports of each pair and a' a' the lower. The head G contains the exhaust-valve I, (shown in details in Figs. 6, 7, and 8,) and consists, likewise, of a wheel or circular ring I, formed with a circular recess i. A segment i' of the peripheral edge of the valve is provided with gear-teeth, and, further, the valve has four ports—two on each side—the upper one of each pair being lettered b and the lower one b'. The exhaust-valve 85 has also the openings c c at points adjacent to the main exhaust-ports, so that the latter may be always open. The steam and exhaust valves are both held in place by means of the covers R R on the outside faces of the casing-heads. When the covers are in position, the valves, by reason of their circular recesses or channels, form steam-chests. The valves, although tightly and neatly located, are capable of rotation to change the position of their 90 ports in reversing, and this rotation is accomplished by gears that engage the segment-gears of the valves, as I shall presently explain.

In the walls of the shell or casing A are 100 steam-passages K K, running horizontally—two on each side of the shell—and they communicate with the interior of the shell through ports k k. In the casing-heads are also pas-

sages for the steam, running at right angles, as shown, and connecting the steam-passages K with the steam and the exhaust valves. (See Fig. 5.) L is the steam-inlet near the steam-valve, (shown in dotted lines in Fig. 3,) and M is the outlet near the exhaust-valve and shown in dotted lines in Fig. 1.

The partial rotary motion is imparted to the valves to shift the same, when desired, by 10 means of the following devices: An upright lever-handle N is fixed upon a horizontal bar N', at each end of which is secured a downwardly-extending rod N². These rods N² N² are secured to the outer ends of shaft O O, 15 which have their inner ends suitably journaled in bearings in the casing-heads. The shafts O O carry gear wheels or pinions O' O'. Said shafts or spindles have the stuffing boxes and glands O² O², whereby tight joints are 20 formed. One of the pinions O' engages the segment i' on the exhaust-valve and the other pinion O' engages the segment h' on the steam-valve. Thus it is evident that by grasping the handle N the engineer may cause both 25 the valves to be rotated sufficiently to reverse the engine.

D' D' represent bushings located in the casing-heads and around the main shaft D. These bushings are renewable in case of wear, 30 and hence can easily be replaced at any time.

P P in Fig. 4 denote packing-pieces, which are adjusted by means of screws p p.

The operation of my improved reversible steam-engine may be briefly stated as follows: 35 When the lever-handle is vertical, as indicated at Fig. 1, the engine will be at rest with valves closed. Suppose, now, the handle to be moved in one direction into an inclined position, as shown in Fig. 3, in consequence of 40 which the valves will be shifted so that the steam-valve will have two diagonally-opposite ports—that is, one port a and one port a' in coincidence with two steam-passages, said port a being opposite one of the upper steam-passages and said port a' being opposite one of the lower passages. (See Fig. 3.) Likewise it is 45 obvious that the exhaust-valve will occupy a position where two of its ports will come into coincidence with two of the steam-passages. 50 Steam entering the engine through the inlet L will now pass through the steam-valve and out through ports a a', and on through the passages K K and ports k into the interior of the cylinder, where it will act on the blades, 55 causing the shaft D to revolve in the usual manner. The steam will then exhaust through the ports at the other end of the engine. J denotes the main exhaust-ports. If, now, it is desired to reverse the operation of the engine, 60 the engineer can lay hold of the lever-handle and shift the same into an inclined position on the other side of the perpendicular. This will shift the valves and cause the steam-valve to bring its port into coincidence with 65 the other steam-passages, so that steam will be admitted so as to act upon the other side of the blades. Of course it may be also stated

that the exhaust-valve will have its ports properly changed to permit the exhaustion of the steam consequent upon its changed course 70 through the engine. In this way the revolution of the rotary cylinder will be reversed, the steam acting upon the other sides of the blades. Thus it will be seen that at any time the engineer may, by laying hold of and reversing the lever-handle, cause the engine to be reversed and to run in an opposite direction. 75

Having thus described my invention, what I claim as new, and desire to secure by Let- 80 ters Patent, is—

1. In a steam-engine, the combination of the shell or casing, the rotary cylinder within the same, the sliding blades with which said cylinder is provided, the annular exhaust and 85 steam valves provided with suitable ports, and the devices for simultaneously rotating the same so as to reverse the engine.

2. In a steam-engine, the combination of the shell or casing, the rotary cylinder and its 90 shaft, the series of sliding blades with which said cylinder is provided, the casing-heads at each end of the casing, the cam connected thereto upon which the sliding blades operate, the ports and passages in said casing and 95 heads, the steam-inlet valve and the exhaust-valve, each consisting of an annular ring provided with suitable ports, and devices for imparting to these valves a simultaneous rotary motion. 100

3. In a steam-engine, the combination, with the shell or casing, the rotary cylinder, and the sliding blades, of the steam-inlet valve consisting of an annular ring having a recess and ports, and the steam-exhaust valve consisting, 105 likewise, of an annular ring having a recess and ports, said steam and exhaust valves being arranged so as to be capable of a partial rotation.

4. In a steam-engine, the combination of the 110 steam-valve having an annular recess and suitable ports, the exhaust-valve, likewise having an annular recess and suitable ports, and the devices consisting of gears that engage these valves, and operating-levers for said 115 gears, whereby the said valves may be simultaneously rotated so as to reverse the engine.

5. The combination, with the shell or casing, the rotary cylinder and its shaft within the same provided with moving blades, the casing-heads, and the cams, of the steam-valve having an annular recess, the exhaust-valve likewise having an annular recess, said valves being arranged in the heads so as to be capable of rotation, the devices for imparting a simultaneous movement to these valves, the valve-covers, steam-inlet, and suitable ports and passages arranged as specified. 125

6. The combination, with the shell or casing and its rotary internal parts, together with 130 suitable ports and passages, of the steam-valve consisting of an annular ring having a circular recess, suitable ports, and a segment-gear, and the exhaust-valve consisting, like-

wise, of an annular ring with an annular recess, suitable ports, the cut-away part, and the segment-gear, and the devices for simultaneously moving these valves, consisting of a lever-handle and pinions engaging the segments of the valves.

7. In a steam-engine, the combination, with the shell or casing and the rotary blade-provided cylinder within the same, of the steam-valve H, having recess h and ports a a a' a' and segment-gear h', the exhaust-valve I, having recess i, ports b b b' b', openings c c, and segment-gear i', the pinions O', engaging the segments, and the lever-handle carried by the horizontal bar connected to the shafts on which are mounted the said pinions O' O', all as herein stated.

8. In combination with the shell or casing of a steam-engine, the rotary valve adjacent to the steam-inlet, having a segment-gear, and a rotary exhaust-valve adjacent to the steam-exhaust, having, likewise, a segment-gear, the

pinions O' O', engaging said segments and located on the shafts O O, and the lever-handle N, affixed to the bar M', which connects 25 with the shafts O O by the bars N² N².

9. The combination, with the shell or casing, of the sliding blades with which said cylinder is provided, the casing-heads, the rotary steam-valve in one head and the rotary exhaust-valve in the other, each consisting of an annular ring provided with suitable ports, the cover-plates for said valves, the steam-inlet and the steam-outlet, and the devices for 30 35 imparting simultaneous movement to the two valves, as specified.

In testimony whereof I affix my signature in presence of two witnesses.

JOHN MOFFET.
